UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

PERCUSSIVE-TOOL FRONT-END CONSTRUCTION.

Application filed November 26, 1920. Serial No. 426,671.

To all whom it may concern:

Be it known that I, FRANCIS A. JIMERSON, a citizen of the United States, and resident of Athens, county of Bradford, State of Pennsylvania, have invented a certain Percussive-Tool Front-End Construction, of which the following is a specification.

This invention relates to fluid actuated machines of the hammer type, but more particularly to an improved front end construction for core breakers, coal picks, and similar machines, having a working tool in the form of a steel provided with a collared shank, adapted to extend into the cylinder in position to receive the impact blows of the hammer.

Means have heretofore been provided around the steel shank and between the fixed collar on the shank and the enclosing barrel nut for cushioning the steel, and this cushioning means has usually been in the form of a spring, but such springs have been found to break and are short lived. It has furthermore been found to be practicably impossible to make springs of suitable sizes which will continuously withstand the severe shock to which they are subjected without weakening, and injury to the machines has resulted from such breakage, with the attendant delays in the work.

The primary object of the present invention is to secure a simple and efficient cushioning device which cannot break under all ordinary circumstances and will be long-lived and save breakage and repairs. I have found that a buffer of some suitable elastic material other than metal, of which rubber may be taken as an example, has many advantages over a metallic spring. The buffer should be of some material which has substantially the qualities of comparatively soft pliable vulcanized rubber, rather than hard rubber and the material of the buffer should have appreciable elasticity. The buffer whether of rubber or other material, is located within the barrel nut forming the front head of the machine and forwardly of the fixed collar on the shank of the steel, and a loose metallic buffer collar is preferably arranged between the buffer and the said fixed collar on the shank of the steel. A washer may also be provided ahead of the buffer and over the opening in the end of the barrel nut through which the working end of the steel is passed in assembling the

parts, so that said washer closes the opening, protects the buffer and prevents the buffer from squeezing through the hole in said end, although as will appear, this protective washer may if desired, be omitted. 60

The improved front end construction and cushioning device are illustrated in one of their preferred forms in the accompanying drawings in which—

Figure 1 is a longitudinal sectional elevation of the front end of a machine containing the invention, 65

Figure 2 is a side elevation, and

Figure 3 is a detail side view of a portion of the shank of a steel illustrating one 70 method of applying the buffer and washer to the shank.

Referring to the drawings, only so much of the front end of a fluid actuated machine of a hammer type is shown as will serve to 75 illustrate the invention. In this instance a coal pick has been chosen to illustrate the invention, but the invention applies equally well to core breakers and similar machines. The cylinder A, of which only the front end 80 portion is shown, is adapted to receive the shank B of a steel forming the working tool, in this instance, having a collar C. The shank extends through the sleeve D in the cylinder into position to receive the impact 85 blows of the fluid actuated hammer E in the usual manner. The sleeve D surrounds the shank of the steel rearwardly of the collar C and extends into the cylinder, whereby the collar C has limited movement between the sleeve and collar F. 90

A loose collar or thick heavy washer F in this instance loosely surrounds the shank of the steel forwardly of the fixed collar C and receives the concussion of the steel as it is 95 driven forward by the blows of the hammer.

In accordance with the form of the invention illustrated, a cylindrical non-metallic elastic buffer G of suitable material as rubber of substantially the quality described, is 100 placed loosely over the shank of the steel and is adapted to contact with the loose collar F. In Figure 3, the buffer G is shown in position on the shank of the steel. The use of a buffer collar F is advisable in order 105 to eliminate to a large extent the wear of the steel on the buffer, which would otherwise occur.

A split metallic buffer washer H of substantially the same diameter as the normal 110

outside diameter of the buffer G, is placed on the shank on the steel in front of the buffer, and in Figure 3 the buffer washer is shown in position on the shank in full lines, 5 and is shown in dotted lines in the act of being placed on the shank. The split washer H is opened or forced apart as indicated in dotted lines and is thus sprung over the shank of the steel.

10 This buffer washer H is preferably split and punched with a shape to correspond to the form of cross section of the steel, so that it will hug the steel closely. This split washer H could be omitted and is not a necessary, although a desirable part of the construction, inasmuch as the hole J in the front end K of the barrel nut L in the case of a coal pick is relatively small and does not need to be large enough to permit the fixed collar C of the steel to pass through as in 20 the case of a tie tamper for instance in which the tamper steel is provided with an enlarged and broadened working end.

The barrel nut L forming the front head 25 of the machine encloses the buffer collar F, the buffer G and the buffer washer H as illustrated particularly in Figure 1, and extends over the front end of the cylinder A. The buffer washer H between the buffer G 30 and the end K of the barrel nut closes the opening J in the end of the barrel nut and when the parts are assembled, protects the buffer, and prevents the buffer from becoming distorted and damaged by shock and 35 pressure which might otherwise tend to force the material of the buffer through the aperture J.

The barrel nut L is preferably threaded onto the forward end of the cylinder A by 40 means of the screw threads O and suitable means may be provided for retaining or locking the barrel nut in position after it is tightened, in this instance the inner edge of the barrel nut being provided with grooves 45 or notches P adapted to receive the bent end Q of a coiled spring R the other bent end S of which enters the notch T in the flange U on the cylinder A.

50 After the parts are assembled and the barrel nut L is attached and securely retained in position, the shock of the collar C of the steel upon the loose collar F is cushioned by the collar retaining buffer G which has the double function of a cushioning and 55 retaining device. The buffer washer H may have the double function of a retaining and protective device. This cushioning device has been found to operate satisfactorily and well, prolongs the life of the parts and does 60 not need to be renewed except in occasional instances.

I claim:

1. A fluid actuated machine of the hammer type, having a fluid pressure cylinder, 65 a working tool in the form of a steel hav-

ing a collared shank adapted to extend into the cylinder in position to receive the impact blows of the hammer, a collar loosely surrounding the shank of the steel forwardly of said fixed collar on the steel and 70 adapted to receive the impact of the steel as it is driven forward, a sleeve surrounding the shank of the steel rearwardly of said fixed collar and extending into the cylinder, whereby the fixed collar on the steel 75 has limited movement between the sleeve and loose collar, a collar retaining buffer loosely mounted on the shank of the steel and adapted to contact with said loose collar and cushion the blow of the steel, a barrel nut forming a front head enclosing said buffer and collar and secured to the front end of the cylinder, the said barrel nut having an opening in its front end to permit the passage of the working end of the steel, 80 and means for retaining the barrel nut in position on the cylinder.

2. A fluid actuated machine of the hammer type, having a fluid pressure cylinder, 90 a working tool in the form of a steel having a collared shank adapted to extend into the cylinder in position to receive the impact blows of the hammer, a collar loosely surrounding the shank of the steel forwardly of said fixed collar on said steel 95 and adapted to receive the impact of the steel as it is driven forward, a sleeve surrounding the shank of the steel rearwardly of said fixed collar and extending into the cylinder, whereby the collar on the steel has 100 limited movement between the sleeve and the collar, a non-metallic elastic collar retaining buffer loosely mounted on the shank of the steel forwardly of said loose collar adapted to cushion the blow of the steel, a 105 split metallic buffer washer in front of said buffer, a barrel nut enclosing said loose collar, the buffer, and the washer, and extending over the front end of the cylinder, and means for retaining said barrel nut in position on the cylinder.

3. A fluid actuated machine of the hammer type having a fluid pressure cylinder, 110 a working tool in the form of a steel having a collared shank adapted to extend into the cylinder, in position to receive the impact blows of the hammer, a collar loosely surrounding the shank of the steel forwardly of said fixed collar on said steel 115 and adapted to receive the impact of the steel as it is driven forward, a sleeve surrounding the shank of the steel rearwardly of said fixed collar and extending into the cylinder, whereby the collar on the steel has 120 limited movement between the sleeve and loose collar, a non-metallic elastic collar retaining buffer loosely mounted on the shank of the steel adapted to contact with the said loose collar and to cushion the blow 125 of the steel, a split metallic buffer washer 130

on the shank of the steel in front of said buffer, a barrel nut enclosing said collar, the buffer, and the washer, and extending over the front end of the cylinder, the said 6 barrel nut having an opening in its front end to permit the passage of the working end of the steel, and the buffer washer forming a cover for said opening when the parts are assembled, and means for retaining the 10 barrel nut in position on the cylinder.

4. A fluid actuated machine of the hammer type, having a fluid pressure cylinder, a working tool in the form of a steel having a collared shank adapted to extend into 15 the cylinder in position to receive the impact blows of the hammer, a collar or heavy washer loosely surrounding the shank of the steel forwardly of said fixed collar on said steel, and adapted to receive the impact 20 of the steel as it is driven forward, a sleeve surrounding the steel and extending into the cylinder rearwardly of said collar,

whereby the collar on the steel has limited movement between said loose collar and sleeve, a non-metallic elastic collar retaining buffer loosely mounted on the shank of the steel, adapted to cushion the blow of the steel, a split metallic buffer washer on the shank of the steel in front of said buffer, a barrel nut enclosing said loose collar, the 25 buffer and the washer, and extending over the front end of and removably secured to the cylinder, the said barrel nut having an opening in its front end to permit the passage of the working end of the steel, and 30 the buffer washer forming a closure for said opening when the parts are assembled, and means comprising a coiled spring retained in the groove in the barrel nut and a notch in the cylinder for retaining the barrel nut 35 in position on the cylinder.

In testimony whereof I have signed this specification.

FRANCIS A. JIMERSON.
